FIRE DEPARTMENT HAND TOOL

Filed Nov. 2, 1927

INVENTOR,

C. E. McKeag;

BY

G. E. Maynard, ATTORNEY.

UNITED STATES PATENT OFFICE.

CHARLES E. McKEAG, OF LOS ANGELES, CALIFORNIA.

FIRE-DEPARTMENT HAND TOOL.

Application filed November 2, 1927. Serial No. 230,597.

This invention relates to a hand tool designed for fire-department use.

A fireman, in his fire-fighting duty, cannot be hampered by carrying several different tools each having a single function, since this equipment would be an impediment to his activity at work and materially reduce his efficiency as a fire fighter.

In his work a fireman is called upon to employ a wrench to turn on and turn off water-plug valves, to use a tool for connecting and for disconnecting a hose coupling, to use an implement to break glass, and has to grasp and carry, in the best manner possible, empty (flat) hose and hose filled with water under pressure and sometimes ice-coated. He is called upon to extricate trapped individuals and to attempt to carry one or more individuals some actively resisting, some unconscious, and some lifeless. There are other exigencies too numerous to mention.

Being well acquainted with the practices of men of fire departments at work, my object is to provide a tool to meet, by reason of its construction and arrangement of elements, many of the fireman's tasks and at the same time not impose an undesired burden of weight or awkwardness of application.

Other objects, advantages, and features of construction, combination, and arrangement of parts will be made manifest in the following specification of the herewith illustrated embodiment; it being understood that modifications, variations, and adaptations may be resorted to within the spirit, scope, and principle of the invention as it is more directly claimed hereinafter.

The drawing is a perspective of the tool as used to support a hose line.

The implement consists of a hose spanner wrench 2 whose head is extended into a handle or shank part 3 which terminates in a hook 4 the plane of which lies at a right-angle to the spanner head 2. Preferably there is interposed between the shank 3 and the end hook 4 a valve-stem socket wrench 5.

The hook 4 has its bow provided with a flat hammering face 6.

One of the important features of the invention is the provision of a closed loop or eye 10 on one side of the handle 3 and intermediate its shank part. The loop is dis-

posed perpendicular to the shank and also at a right-angle to its axis so that the loop will 55 fit comfortably between the second and third fingers of a hand grasping the shank 3. At the connection of the loop to the shank 3 are rounded base fillets 11 to give strength to the parts and also to afford a comfortable 60 grip for the fingers.

Swiveled on the loop 10 is a strong strap 12 of flexible material having an open-end hitch hook 13 which is adapted to be slipped across the strap 12 to form a bight about a 65 section of hose H which can thereby be easily hauled around from place to place, or up ladders and fire-escapes and stairs. The hook 4 can be caught over the fireman's belt when he has attached the strap to the 70 hose and thus leave his hands free for climbing or other use, or the hook 4 can be thrown onto a suitable convenient support and left to suspend the hose held in the strap 12.

An important use of the strap 12 is that, in emergency, the fireman may attach it around the wrist or legs of a human and thereby drag him or her while carrying another over a shoulder, in cases of rescue. 80

Another use of the hook and strap combination is in cases where all escape is cut off the fireman or other individual can hang suspended with the strap 12 caught around a wrist and the hook 4 resting on a window 85 sill pending arrival of rescuers. The strap is particularly useful in the handling of ice-coated hose.

The hook 4 is useful for knocking out glass and for tearing down lath, shingles, light 90 partitions, and for pulling hot timbers in rescuing individuals who are pinned down and when removing bodies of fire victims. The strap may be used in many cases for dragging away timbers, iron elements, and 95 other débris.

The invention claimed is:

1. A fireman's hand tool having a handle shank with an integral loop member extending out at one side and between its ends, a 100 strap attached to said loop and adapted to be attached to a body or object to be hauled or suspended, and a suspending hook on one end of the handle whereby the tool may be hooked onto a convenient support to suspend 105 a load in the strap.

2. A fireman's wrench having a handle shank with an integral loop extending out on one side and disposed at a right-angle to the axis of the shank so that the loop will lie between the fingers of a hand grasping the shank, and a grappling strap attached to the loop.

3. A fireman's hand tool including a shank which is provided with a perpendicular, transverse strap-receiving loop, and having ¹⁰ on one end a hook by which the tool may be suspended.

CHARLES E. McKEAG.
